GAME TABLE

Eero A. T. Paasikallio, Kuopio, Finland, assignor to Veikko Matilainen & K:Ni Ky

Filed Feb. 25, 1974, Ser. No. 445,585

Term of patent 14 years

Int. Cl. D21—01

U.S. Cl. D34—5 J

The figure is a perspective view of a game table showing my new design. The sides not shown are similar to the side shown.

I claim:

The ornamental design for a game table, as shown and described.
